Specification of Letters Patent.

Patented May 8, 1917.

Original application filed September 9, 1915, Serial No. 49,687. Divided and this application filed March 8, 1917. Serial No. 153,337.

To all whom it may concern:

Be it known that I, HARRY F. STRATTON, a citizen of the United States, residing at Cleveland, in the county of Cuyahoga and State of Ohio, have invented new and useful Improvements in Electromagnetic Apparatus, of which the following is a specification.

My invention relates broadly to electric controllers, and more specifically to electromagnetic switches for controlling the acceleration of alternating current motors from standstill to normal running speeds. This invention is a division of my application Serial Number 49,687, filed September 9, 1915.

One object of this invention is to provide for alternating current motors a starting switch which provides a single operating magnet for first connecting the motor to the supply mains through a voltage-reducing means such as a transformer, and subsequently connecting the motor directly to the mains; to provide the aforesaid switch with a mechanism which permits the armature of the operating magnet to move to its full closed position immediately upon energization of the magnet, whereby the magnet is not left with its magnetic circuit open while the starting switch is in the starting position; to provide a means for releasing the starting switch when in starting position whenever the motor current drops to such a value that it will, on the movement of the switch to the running position, rise to a value substantially equal to the initial value of the current irrespective of the voltage of the starting current; to provide in the apparatus a mechanism whereby the starting switch, when released, will be automatically removed from the starting to the running position by power stored up by the closing movement of the magnet armature; to provide starting and running contacts, and a set of movable contacts for moving into successive engagement therewith, and constrained by a mechanism to move from the starting position to the running position, and thence to a neutral position without passing through the starting position; to provide contacts of such form that upon closure the shock of impact will be absorbed and will not cause a momentary separation and arcing of the contacts; and to pro-

vide a starting magnet for the aforesaid purposes which will be cheap to construct, durable, and efficient in its operation. Further objects will appear hereinafter.

Referring to the accompanying drawings, Figure 1 is a side elevation of an apparatus containing the principle of my invention, parts being in section; Fig. 2, a top plan view of the said apparatus with the cover of the casing and the bar 18 removed; Fig. 3, a vertical section on the line 3-3, Fig. 1; Fig. 4, a side elevation of the switch-operating magnet, and adjacent parts, portions being in section and broken away; Fig. 5, a partially diagrammatic view of the switch mechanism in neutral position; Fig. 6, a view like Fig. 5, except that the switch mechanism is shown in the starting position; Fig. 7, a typical diagram of one of several electric circuits which I may employ in connection with a squirrel-cage motor; Fig. 8, a diagram of curves illustrating the use of my invention with currents of different values; and Fig. 9, a section through the pivot 26 and the parts connected thereby.

On the drawings, 10 designates an oil-containing casing or tank having the contracted lower portion 10'; bosses 11 being provided on the shoulder which connects the said contracted portion to the upper portion of the casing.

13 is a U-shaped casting constituting the main frame for supporting the various parts of my invention. The member 13^a of the frame has the arms 14, and the other member 13^b, the arms 15, the said arms having their ends 16 resting on the bosses 11 and provided with the centering pins 12 fitting in holes in the said bosses. The T-bar 18 is secured to the upper ends of the members 13^a and 13^b, and constitutes a support by which the frame 13 and the parts carried thereby may be lowered into the casing and removed therefrom.

The transformer T, which in the present instance is a three-phase auto-transformer with the open delta coils 19 and 19^a and the core 20, is supported by the frame 21 secured to the under side of the frame 13. The coils are each shown with the taps t and the open or upper end connections t'. The lower ends of the coils are connected to the common conductor T'.

I employ a magnet having the U-shaped

laminated core 22 provided with the magnetizing winding O wound on the cast-metal spool 23 which surrounds the lower leg of the core. The laminations of the core are 5 secured together by the transverse strips 68 of welding material, the rear strips being welded also to the plates 69 which are bolted to the inner face of the member 13^a. The spool has preferably integral therewith the 10 legs 74 bolted to the lower plate 69. Its upper side is shown with a slit extending entirely across the same to prevent the induction of currents in the spool. 75 is a 15 spacing rod of fiber or other insulating material seated in grooves in opposite walls of the said slit to maintain the slit at the desired width.

To prevent the chattering of the armature 24 on the upper pole of the magnet, 20 I embed a portion of a closed conductor or loop in the face of the said pole. This conductor comprises two members, one a strip of metal 70 resting on the support 72 and having its intermediate portion embedded as described and its end portions bolted to the second member 71, preferably a corrugated casting which introduces a resistance into the closed loop and radiates heat produced in the loop by currents induced therein by the alternating flux in the upper pole piece and generated by the winding O which is connected by the switch S across two of the line conductors L. The flux induced in the upper pole by the loop 30 alternates with the flux produced by the winding O, whereby the said pole continuously holds the armature 24 against it.

The armature 24 is welded by the transverse strips '68' to the upstanding member 40 of the lever 25 pivoted between its ends on the pin 26, which fits loosely in the lever whereby the pin will not interfere with any movements of the lever required to make the armature fit squarely on the upper pole of 45 the magnet and squarely on the plate 77 held loosely between the armature and the lower pole of the magnet. This plate has at its ends holes to receive the two studs 76 projecting from the face of the spool 23, the 50 holes being slightly larger than the studs in order that the plate may adjust itself so as to rest squarely against the lower pole. The studs 76 have the cotter pins 78 to keep the plates from sliding off therefrom. The plate 77 is made of wearing-resisting, non-magnetic material having high resistance, such as nickel steel. It serves to maintain 55 a non-magnetic gap to prevent the armature from sticking to the lower pole when the winding O is deenergized. The high resistance of the plate prevents excessive heating by eddy currents.

The pin 26 is supported by the base of 60 the frame 13 below the armature 24, and 65 is preferably composed of non-magnetizable

material to reduce the flux flowing through the pivotal connection between the frame 13 and the lever 25.

The lever 25 carries above the pivot 26 the horizontal pivot pin 27 on which the 70 upwardly-extending movable switch member 28 and the upwardly-extending stop-arm are mounted to swing. The stop-arm 29 carries the pivot 30 to which one end of the link 31 is connected, the other end thereof being connected to one end of the link 32 by the pivot pin 34. The other end of the link 32 is connected to the pivot pin 33 supported by the member 13^b of the frame 13. The links 31 and 32 constitute toggle 80 members, their connecting pivot 34 being beneath a line connecting their end pivots 30 and 33.

The pivot 34 supports the depending upper compression member 35. A spring 36 85 has its upper end seated on the lower end of the compression member 35, and its lower end on the upper face of the lower compression member 37, which is provided with a centering core 36' for the spring, the two 90 compression members 35 and 37 being kept in alinement with the axial center of the spring 36 by the stem 36^a, carried by the member 35 and slidable in a central opening in the core 36'. 95

A bell-crank lever 38 is pivoted on the pin 39 supported by the member 13^b near the lower end thereof. One arm of the lever 38 is connected to the lower arm of the lever 25 by the link 40, while the other arm of the lever 38 is pivoted to the lower end of the compression member 37, the latter having an open pivot-bearing to facilitate its removal and replacement. The member 37 is curved so that when the parts are as in 105 Fig. 5 the upper arm of the lever 38 will not interfere with the said member.

The upper end of the stop-arm 29 has three stop surfaces 41, 42, 43, the surfaces 41 and 42 being on opposite sides of the 110 arm 29. The switch member 28 has a recess 44 between the opposite side-walls of which the upper end of the stop-arm 29 moves, the recess being slightly longer than the distance between the stop surfaces 41 and 42, whereby there exists some lost motion between the members 28 and 29, the switch member 28 having a small angular movement on the pivot 27 independently of the stop-arm 29. The stop surface 43 is adapted to rest on the stop 45 on the armature lever 25. 115

46 is a preferably non-magnetic stop on the frame 13 to support the armature lever 25 when in its neutral position, as shown 125 on Fig. 5.

48 is a latch pivoted between its ends on the pin 47 supported by the member 13^b. The lower end of the link 32 has a notch 49 adapted to be caught by a hook, on the 130

upper side of one end of the latch so as to prevent the straightening of the toggle members 31 and 32 by the spring 36 until they are released by the latch. The other 5 end of the latch lies over the upper end of a two-coil tripping device 50, having the movable core 51, separated from a fixed core in the upper coil V by the air-gap 52, and from the adjustable core 67 in the lower 10 coil C by the air-gap 53. These coils exert opposite pulls on the core 51. Under certain conditions, to be explained presently, the pull at the gap 52 preponderates, whereupon the core moves upwardly, and the head 54, connected to the core 51 by the rod 55, strikes the latch 48 and causes the 15 latch to release the link 32 in an evident manner.

The arms 14 and 15 support two slates or 20 other insulating bases 56, the arms 14 being provided for this purpose with additional arms 57. These slates carry a group of spring cushioned stationary starting contacts 58, 58^a, 58^b, and 58^c, and a group of 25 similar running contacts 59 and 59^e. The switch member 28 carries a wooden or other insulating cross-arm 61, on which groups of contacts 62, 62^a, 62^b, and 62^c are mounted.

With the parts in the neutral position 30 shown on Fig. 5, it will be noted that the latch is in locking engagement with the link 32, the spring 36 is in its expanded condition, the armature 24 is in its unattracted or neutral position, and the armature lever 25 rests on the stop 46. These parts assume 35 these positions under the action of gravity and the compression spring 36 when the winding O is deenergized. When the winding O is energized, the armature 24 is drawn to the core 22 and carries the lever 25 with it. The latch 48 prevents any movement of the toggle member 32, so that, as the pivot 27 moves forward with the lever 25, the arm 29 swings on the pivot 30, causing the end of 40 the arm 28 above the pivot 30 to move toward the starting contacts and finally to move the contacts 62, 62^a, 62^b, and 62^c into engagement with the said starting contacts, as shown on Fig. 6. While the operation just described 45 is taking place, the lever 25 has, through the link 40, turned the bell-crank lever 38 from the position shown on Fig. 5 to that shown on Fig. 6, the lower arm of the lever 38 moving upwardly from its neutral or idle position 50 below its pivot 30 so as to cause the spring 36 to be compressed between the compression members 35 and 37. The parts will remain as in Fig. 6 until the tripping device 55 operates to release the latch 48, whereupon the spring 36 will cause the toggle members 31 and 32 to be extended and the switch member 28 to be moved into the position shown on Fig. 1, in which the movable contacts 62^a and 62^c are shown in engagement 60 with the running contacts 59 and 59^c,

respectively, and the said movable contacts are shown disconnected from the starting contacts. The parts will remain in this position until the winding O is deenergized, when they will return to the neutral position 70 shown on Fig. 5.

The blow of the movable contacts 62 upon the starting or the running contacts, causes the latter to overtravel a slight distance. If the movable contacts came inflexibly into engagement with the starting or running contacts, this overtravel of the latter would cause a momentary opening of the electrical circuits established by the engagement of the movable and the starting or running 75 contacts. To prevent this momentary interruption of the circuits, I provide sufficient lost motion between the stop arm 29 and the movable switch member 28 to which the movable contacts are rigidly connected, so that the latter may follow the starting or running contacts in their overtravel and may thereby maintain continuous contact with the starting or running contacts as long as the movable contacts are in the starting or running position respectively. It will be understood that the overtravel of the starting or running contacts and the coördinating follow-up of the movable contacts are but momentary and that both contacts rapidly assume their normal positions under the influence of the cushioned springs which co-operate with the starting or running contacts. 80

On the casing 10 is a row of terminals 63, 100 63^a, 63^b, 63^c, 63^d, and 63^e. The motor lead M^c and the contact 62 are connected to the terminal 63. The motor leads M^a and M^b are connected to the terminals 63^a and 63^e respectively. The terminals 63^a and 63^c are 105 connected together by the wire N. The contacts 59 and 62^a are connected to the terminal 63^b, and the contacts 62^b and 59^e to the terminal 63^c. The three-phase supply mains L^a, L^b, and L^c are connected to the terminals 110 63^d, 63^e, and 63^b, respectively. The winding O has one end connected to the terminal 63^b and the other end to the terminal 63^c through the master switch S. The motor is indicated by the letter M and is of the squirrel-cage type with star-connected stator windings, but I do not limit myself to any definite type of motor or any definite arrangement of windings therefor. 115

On the member 13^b of the frame 13 I 120 mount the insulating block 64 which supports a row of horizontal terminals 65, 65^a, and 65^b, and a row of terminals 66 and 66^a, having sockets to receive the ends of the wires t and t'. The current coil C has its 125 ends connected to the terminals 65 and 65^a in series with the motor current, and the voltage coil V has its ends connected across the conductor T' and the conductor containing the coil C. It will be noted that the coil 130

V is energized by the secondary voltage of the transformer and not by the line voltage, and that the voltage on the coil V will automatically be changed when the transformer taps are adjusted to change the motor starting voltage. The voltage coil V has, preferably in series therewith, the non-inductive high resistance H, which is designed to prevent a high current transient, which might occur in the said coil when first excited, from exerting a sufficiently large pull across the gap 52 to lift the core 51 and trip the latch 48 prematurely.

The four taps t to the winding 19 of the transformer T are connected to the four outer terminals 66 at one end of the block 64, and the four taps t to the winding 19^a of the transformer are connected to the four outer terminals 66^a at the other end of the said block. The open ends of the windings 19 and 19^a are connected by the wires t' to the two inner terminals 66 and 66^a, the latter being connected respectively to the contacts 58^a and 58^b by the flexible conductors t^a and t^b. The flexible tap-connector F^c has one end connected to the terminal 65, its other end being removably connected to any selected one of the four outer terminals 66, and the flexible tap-connector F^b has one end connected to the terminal 65^b and its other end detachably connected to any selected one of the four outer terminals 66^a. The terminal 65^a is connected to the contact 58 by the flexible conductor t^a, and the terminal 65^b is connected to the contact 58^b by the flexible conductor t^b. The terminals 66 and 66^a are preferably above the level of the oil in the tank, so that the tap connectors F^b and F^c may be changed at will to suitably selected terminals 66 and 66^a without removing the apparatus from the oil.

Suppose the parts to be in their neutral positions, as shown on Figs. 5 and 7. To start the motor M the switch S is closed, causing the winding O to be energized and the parts to be moved, as already described, to the starting position shown on Fig. 6, in which the contacts 62, 62^a, 62^b, and 62^c are in engagement with the starting contacts 58, 58^a, 58^b, and 58^c, respectively. In this position the supply main L^b is connected through the contacts 62^b and 58^b to the open terminal of the transformer winding 19^a, and the supply main L^c is connected through the contacts 62^a and 58^a to the open end of the winding 19, the supply main L^a being always connected to the remaining ends of the transformer windings irrespective of the starting switch contacts. The motor lead M^c is connected to the second terminal 66 through the contacts 62 and 58, the current coil C and the tap-connector F^c. The motor lead M^b is connected to the second terminal 66^a through the contacts 62^c and 58^c and the tap-connector F^b, the motor lead

M^a being always connected to the common point T' through the conductor N. Thus, only a portion of the transformer is connected to the motor leads M^b and M^c, causing the motor to start under a voltage less than the line voltage. For any given connection of the tap connectors F^b and F^c with the tap terminals 66^a and 66, the upward pull of the coil V on the core 51 remains practically unchanged for the same line voltage, but the downward pull on the core varies with the current through the motor. When the switch member 28 is first moved into starting position, the rush of current in the coil C causes the downward pull on the core 51 to overpower the upward pull thereon caused by the current in the coil V. When the motor current decreases to such a value that the pull produced by the coil C is overpowered by the pull produced by the coil V, the latch 48 is tripped in the manner hereinbefore explained, and the parts move to the running position (Fig. 1), in which the supply main L^b is connected directly to the motor lead M^b through the contacts 59^c and 62^c, and the supply main L^c is connected directly to the motor lead M^c through the contacts 59 and 62, the supply main L^a being connected to the motor lead M^a through the conductor N. The transformer and the coils C and V are disconnected from the supply mains L^b and L^c, and the full voltage of the source of current supply is impressed on the motor, whereby the motor is quickly accelerated to running speed. When the winding O is deenergized the switch member 28 quickly assumes its neutral position shown on Fig. 5, with the latch 48 in locking engagement with the toggle member 32.

The length of the gap 53 may be adjusted by screwing the plug up or down in the bottom member f of the E-shaped magnetizable frame which supports the windings C and V and constitutes portions of the magnetic circuits. I adjust the gap 53 so that the pull produced by the coil V will overcome the pull produced by the coil C when the motor current is reduced to such a value that the closing of the running contacts will cause the current to rise to the initial value, that is, to the value of the current impressed on the motor at the instant the starting contacts are closed. The ampere turns of the coils C and V are relatively so proportioned that the magnetic circuit of the coil C is energized at higher degrees of magnetization than that of the coil V, and the adjustment just described is made when the tap connectors F^b and F^c are on that part of tap terminals 66 and 66^a which give the lowest motor starting voltage. When the tap connections are changed to give higher starting voltages, the magnetic flux of the coil V will increase approximately in

proportion to the voltage, but the flux of the coil C will not be increased in proportion to the motor current at the higher voltage because the magnetic circuit of the coil C is 5 more nearly saturated than that of the coil V. It will thus be seen that as the starting voltage is adjusted the ratio between the voltage and the current at which the tripping device 50 operates, will decrease as the 10 starting voltage is increased. When the gap 53 of the trip device 50 has been adjusted, as just described, with the tap connectors F^b and F^c on one pair of tap terminals 66 and 66^a, no adjustment is required to adapt it 15 to changes of voltage and current values caused by connecting the tap-connectors to any other pair of tap terminals. This important characteristic of my invention is graphically illustrated on Fig. 8, in which 20 the three curves in solid lines indicate the current flowing through the motor during its acceleration with three different voltages impressed on the motor. If the motor is started on voltage B and initial current *ob*, the trip device 50 operates to trip the latch 48, so that, when the transition to full line 25 voltage occurs, the current through the motor will rise to its initial value *ob*. The line *b b'* is drawn parallel to the line *o o'*, its end *b'* meeting the line voltage curve. The line *o' b'* is drawn parallel to the line *o b*. The line drawn from *o'* to the intersection *b'* of the line *o' b'* with the curve for voltage B, obviously represents the current 30 value at which the transition to full line voltage should occur.

If the tap connectors F^b and F^c be changed so as to start the motor on a higher voltage, as voltage A, the initial current 40 through the motor will be *oa*, and the transition to full line voltage will take place when the current drops to the value *o''a'*, the point *a'* being at the intersection of the curve for voltage A with the line *o'' a'*, 45 parallel with the line *o a*, the point *a'* being in the curve for line voltage. The trip device 50 will operate to cause the successive accelerating current peaks to be substantially equal while constant voltage is being 50 impressed on the motor. The peaks for voltage A will be higher than for voltage B, but if the windings of the coils C and V are proportioned properly the peaks for voltage A will be approximately equal to 55 each other and those for voltage B will also be approximately equal to each other. I do not limit myself to the ideal theoretical operation just given, as in practice it may sometimes be preferable not to have equality 60 of current peaks as described, but merely to cause the transition to occur in such a manner that progressively higher currents will occur at transition with the use of progressively higher starting voltages. Although 65 I have, for simplicity described only the

ideal theoretical operation having equality of current peaks, my invention broadly comprises all means for increasing automatically and self-adjustably the current peaks at the transition to line voltage when higher starting 70 voltages are employed.

The described coördinated mechanism permits the armature 24 to close the magnetic circuit of the operating magnet immediately upon energization, thereby preventing the waste of the large wattage and the probable destruction of the winding O by overheating, which would occur if the closure of the said magnetic circuit should be delayed until the running contacts are 75 closed. The said mechanism also causes the hardest work of the operating magnet to come at the time when the gaps between the armature and the poles of the magnet have become short and, therefore, when the magnetic pull on the armature has approximated its maximum. From Fig. 5 it is seen that, during the earliest part of the movement of the armature 24 toward the poles of the magnet, the armature has to swing 80 the switch member 28 and the arm 29 on their pivot 27 to the positions shown on Fig. 6, which requires but little power. At the same time the lever 25 moves the lower arm of the lever 38 on nearly a horizontal 85 line, whereby the spring 36 is only slightly compressed. After the contacts 58 and 62 have engaged each other and the lower arm of the lever 38 begins to move upwardly rapidly, the armature 24 has moved so close 90 to the poles of the operating magnet that it is drawn to the same with great power, causing the spring 36 to be placed under high compression, capable of quickly extending the toggle members and moving the 95 parts to the running position shown on Fig. 1, as soon as the trip device 50 releases the latch 48 from the toggle member 32. The arrangement of the moving parts is such 100 that, at the beginning of the movement of the movable contacts from their starting to their running position, the rotative effort about the pin 27, due to the spring 36, is relatively small, but toward the end of said movement and practically during engagement with the running contacts, the rotative effort of the spring 36, acting on the switch member 28, through the toggle levers 31 and 32, is a maximum. Such a design permits 105 the employment of a spring on which minimum compressive effort is required, and leads directly to the use of a smaller and 110 cheaper operating magnet.

The movement of the parts from their starting position to their running position 115 causes the running contacts 59 and 59^a to be moved back from their idle position, thereby placing their springs 60 under compression. The springs 60, reacting through the various parts of the mechanism, tend to 120

move the lower end of the armature about the upper pole of the magnet as a center, toward the lower pole thereof to prevent chattering, the loose fit of the lever 25 on its pivot 26, and of the spacer 77 on its supporting studs 76 permitting the armature to move freely so that it may fit squarely against the upper pole and the plate 77.

10 The movable contacts have a plurality of centers of rotation, which permit the armature to move at once to its closed position and at the same time permit the contacts 62 to 62^c to be moved first to the starting position and subsequently to the running position. The contacts 62 to 62^c do not, owing to the said centers of rotation, travel on a single line from their neutral position to their starting and running positions, 15 and back to their neutral position, but describe a triangular path as shown by the dotted lines near the top of Fig. 6, where the neutral, starting, and running positions are indicated, respectively, by the letters N, 20 S, and R, the arrow heads showing the direction of travel.

While I have shown my invention in connection with apparatus for starting squirrel-cage motors, it is obvious that some of the 30 principles thereof may be applied to direct current apparatus and to alternating current motors controlled by different voltage-controlling means from those shown. I do not limit myself to the use of three-phase 35 source of supply, or to the squirrel-cage type of motor. While I have shown a traction magnet consisting of a two-pole stationary electromagnet and a pivoted armature arranged to be attracted thereto as the 40 source of mechanical power for operating my invention, it will be apparent that manual means or other types of electromagnetic means capable of developing mechanical power and coöperating with the mechanism which I have shown, or with other 45 forms of mechanism, may be employed without departing from the spirit of my invention.

I claim: —

50 1. In an electromagnet, a plurality of poles, a loosely pivoted armature arranged to be attracted thereto, a winding surrounding one pole, a loosely supported non-magnetic separator between said pole and the armature, means providing a continuous pull between a second pole and the armature when the winding is energized with alternating current, and external means causing a thrust of the armature against the pole not having 55 the continuous pull.

2. In an electromagnet, a plurality of poles, a loosely pivoted armature arranged to be attracted thereto, a winding surrounding one pole, a loosely supported non-magnetic separator between said pole and the 60 armature, means providing a continuous pull between a second pole and the armature when the winding is energized with alternating current, a pivot for the armature whereon the 65

armature, means providing a continuous pull between a second pole and the armature when the winding is energized with alternating current, and external means causing a thrust of the armature against the pole not having the continuous pull and exerting a force tending to pull the armature away from the pole having the continuous pull. 70

3. In an electromagnet, a plurality of poles, a loosely pivoted armature arranged 75 to be attracted thereto against a working load, a winding surrounding one pole, a loosely supported non-magnetic separator between said pole and the armature, means providing a continuous pull between a second pole and the armature when the winding is energized with alternating current, means 80 between the working load and the armature whereby the direction and point of application of the load tends to separate the armature from the second pole and to rotate the armature toward the first pole on the second pole as a fulcrum. 85

4. In an electromagnet, a plurality of poles, a loosely pivoted armature arranged 90 to be attracted thereto against a working load, a winding surrounding one pole, a loosely supported non-magnetic separator between said pole and the armature, means providing a continuous pull between a second pole and the armature when the winding is energized with alternating current, and means between the working load and the armature whereby the direction and point of application of the load tends to 95 separate the armature from the second pole and to rotate the armature toward the first pole on the first pole as a fulcrum, the second pole being located intermediate of the second pole and the pivot. 100

5. In an electromagnet, a plurality of stationary poles, an armature arranged to be attracted thereto, an energizing winding for the stationary poles, a loosely supported non-magnetic separator between one pole and the armature, means providing a continuous pull between a second pole and the armature when the winding is energized with alternating current and when the armature engages the said second pole, a loose pivotal connection for the armature whereon the armature may rotate when attracted toward the stationary poles, and whereby the armature may have movement toward and from the first pole without disengaging the armature 110 from the second pole. 115

6. In an electromagnet, a plurality of poles, an armature arranged to be attracted thereto, a winding surrounding one pole, a loosely supported non-magnetic separator between said pole and the armature, means providing a continuous pull between a second pole and the armature when the winding is energized with alternating current, a pivot for the armature whereon the 120 armature 125

ture may rotate toward the poles when attracted thereto and a lost motion connection between the armature and the pivot whereby after said rotation the armature may have 5 a limited rotary movement toward and from the first pole on the second pole as a pivot.

7. An alternating current magnet having a core and an armature, two working gaps between said core and armature, means in 10 one gap for producing a continuous magnetic pull therein when the magnet is energized, an energizing winding for the magnet, a spool for the winding, a spacer made of material having high electrical resistance 15 and low magnetic permeability loosely supported upon the spool in the other gap, the

armature being adapted to move toward the core and strike upon the spacer.

8. An alternating current magnet having a core and an armature, two working gaps 20 between said core and armature, means in one gap for producing a continuous magnetic pull therein when the magnet is energized, an energizing winding for the magnet, and a spacer made of non-magnetic material 25 loosely supported in the other gap, the armature being adapted to move toward the core and strike upon the spacer.
